No. 718,385.

PATENTED JAN. 13, 1903.

C. H. REMINGTON.

RAILROAD SIGNAL.

APPLICATION FILED JUNE 7, 1902.

NO MODEL.

UNITED STATES PATENT OFFICE.

CHARLES H. REMINGTON, OF ROSWELL, TERRITORY OF NEW MEXICO.

RAILROAD-SIGNAL.

SPECIFICATION forming part of Letters Patent No. 718,385, dated January 13, 1903.

Application filed June 7, 1902. Serial No. 110,681. (No model.)

To all whom it may concern:

Be it known that I, CHARLES H. REMINGTON, residing at Roswell, in the county of Chaves and Territory of New Mexico, have invented 5 certain new and useful Improvements in Railroad-Signals, of which the following is a specification.

My present invention relates more particularly to improvements in the railroad-signal mechanism disclosed in my Patent No. 699,488, dated March 5, 1901; and it has for its object to provide a simple, easily-constructed, and positively-operating means for effecting a proper operation of the signal-controlling 10 pull rod, cable, or other flexible connection, and it can be readily adapted for use on embankments, trestles, and culverts without materially changing the generic arrangement of the several parts.

20 In its general nature my present invention comprehends a novel means for effecting a pull strain on the signal-controlling cable or rod in case of the culvert, trestle, or bridge being damaged by fire, washout, or other 25 causes to such extent as to impair the safety thereof; and in its more subordinate features my present invention consists in certain details of construction and peculiar combination of parts, all of which will hereinafter be 30 fully explained, and specifically pointed out in the appended claim, reference being had to the accompanying drawings, in which—

Figure 1 is a cross-sectional view of a culvert or embankment with my improved signal and signal-operating means cooperatively connected therewith. Fig. 2 is a plan view of the bell-crank connections for joining the pull-rod with the signal-operating crank-shaft. Fig. 3 is a vertical section, illustrating one form of the signal devices, operable by the pull strain on the cable or rod connection. Fig. 4 is a view of a modified form of my present invention. Fig. 5 is a view of a further modification thereof, hereinafter fully explained.

In the practical construction, my improvements comprise a weight, preferably in the nature of a heavy stone, buried in the dump or fill of a culvert, or in an embankment adjacent a trestle, and in such manner relatively to the embankment or dump as to provide for a convenient attachment thereto, of a supplemental cable or strain member, con-

nectible with the main cable or signal pull member, in such manner that the disarrangement of the culvert, dump, trestle, embankment, or in case the bridge or trestle burns or becomes otherwise disabled, to impair the danger thereof.

In the simplest form of my invention, as shown in Fig. 1, the weight A is embedded in a dump or fill B, upon which is located the trackway, as shown, and connected with the stone is a strong wire or cable C, which extends up through the fill B and joins with the main 60 or pull cable D, disposed under the cross-ties E and within the housing F, usually an ordinary gas-pipe tubing, which at a point over the stone A is open or separated, as indicated at f, to provide for conveniently connecting 65 the supplemental cable C with the main pull-cable D, the latter being joined with the signal in a manner best shown in Fig. 2, by reference to which it will be noticed the cable D passes over a guide-pulley G and connects 70 with the bell-crank lever H, disposed horizontally upon the cross-ties and having its end h joined by a flexible connection i with the crank I of the rock-shaft II, journaled transversely of the track-bed, extended to 75 one side thereof, and connected with the signal mechanism S, which may be of any suitable construction, but on the score of economy and simplicity of operation is preferably constructed in the manner shown in detail in Fig. 3.

The signal mechanism S comprises a casing s, in which is held a vertically-disposed member s², which carries at its upper end a plate s³, which acts as a cover or top for the casing 90 when the signal is closed down. In the signal mechanism shown a spring or equivalent means is employed for normally forcing the member s² to its uppermost or signaling position when the switch mechanism is released.

At its upper end the member s² carries a reflector-signal s⁴ of any approved construction, and the said member s² also includes a shank s⁵, which cooperates with a trigger or locking device consisting of an inverted-V-shaped 100 body T, provided with a concaved shoulder upon its under side, which acts as a cap or fastener for locking the signal to its down or closed position.

6 designates a disk or wheel mounted upon 105 the shank s⁵, which is held to revolve and en-

gage with the V-shaped trigger T. In operation the wheel 6 strikes the V-shaped trigger, passes by its side, and rolls under the concaved bottom of the trigger to form a stop or 5 lock mechanism.

7 designates a stiff spring attached to the shank or stem, which has for its purpose to take up all the loose slack on the pull or operating wire. By reason of the peculiar connection of the signal devices and the locking means therefor, as described, should the bridge or trestle burn up or a part thereof burn sufficient to heat the operating-wire the tension of the two opposing springs in each 15 signal-box will serve to stretch the operating-wire sufficient to operate the trigger within the signal-box and actuate the signal, and should the bridge be entirely destroyed the signal will be actuated by the springs inside 20 the signal-casing the same as though the bridge had been carried away or thrown out of proper safe condition by water or other causes.

Adjacent the signal-casing is located a vertical guide-rod E, rotatably mounted in brackets e e, projected laterally from the signal-casing, and the said guide-rod has a spiral wing e², with which connects a laterally-extending arm e³, connected with the vertically-30 movable signal-head and provided with a worm or spiral groove in its aperture, through which the guide E passes and which coöperates with the spiral wing e² of the said guide E.

F designates a semaphore mounted on the 35 top of the guide E, of any approved construction, and is preferably provided with two opposite red glasses or signal-faces and two opposite white glasses, the latter being arranged to be moved into position and to show the 40 signal to safety when the signal devices are closed and are at a safety position, and the red glasses are positioned to show when the main signal mechanism is released and elevated to a danger position, it being understood 45 that rotary motion is imparted to the rod E to effect the movements of the semaphore F stated through the medium of the spiral wing e² and the spiral groove in the member e³.

50 In Fig. 5 is illustrated a slightly-modified form of my invention, in which the same is especially arranged for use on a trackway mounted on piles. In this form of my invention the pull member or cable for actuating 55 the signal mechanism is mounted in suitable guides upon the cross-beams B, mounted upon the piles P. In this latter form C⁵ designates a weighted lever inclined downward relatively to the horizontal plane of the 60 beams B and is made fast at its lower end to one of the piles, and the said lever C⁵ is supported at a point between its lower and upper ends in a bracket A⁵, and its upper end is grooved to engage the pull member or cable 65 that actuates the signal mechanism. In this construction it will be apparent that should the pile structure upon which the trackway

is mounted be partly washed away or burned out, so that the end carrying the lower portion of the lever C⁵ sags, the said lever will 70 be by reason of its fulcrum in the bracket A⁵ be swung up in the direction indicated by dotted lines in Fig. 4 and effect a strain upon the pull-rod sufficient to cause it to actuate the signal mechanism. 75

In Fig. 4 is shown a further modification of my invention, in which a high trestle-work is shown, upon which the trackway is mounted. In this construction the pull member or actuating-cable is mounted upon the cross-ties 80 E, and with said member is connected two divergently-arranged cables A⁶ A⁶, that pass down upon the trestle through suitable guides A⁷ at the bottom thereof, from whence they pass off in the horizontal plane with the bottom of the trestle and connect with the weights or anchors C¹⁰, as shown. By arranging supplemental pull devices for actuating or effecting a strain on the signal-actuating member in the manner last described it 90 is manifest that should the trestle sink at one side by reason of a washout or the said trestle be otherwise thrown out of plumb the strain will be imparted to the supplemental wires A⁶ and the pull strain thereof transmitted to the main actuating-cable or signal-operating member. 95

From the foregoing description, taken in connection with the accompanying drawings, it is thought that the advantages of my invention and the manner of its operation will be readily understood. The construction of the same, it will be noticed, is such as to provide for a reliable and durable means for actuating a signal to indicate when a bridge, 105 culvert, trestle, or other similar track-supporting means is disarranged or rendered unsafe.

Having thus described my invention, what I claim, and desire to secure by Letters Patent, is—

A signal-actuating means, comprising in combination a spring-set vertically-shiftable signal, a rotary signal and connections joining the two signals, whereby the movement 115 of the vertically-shiftable signal will set the rotatable signal, a detent mechanism for locking the set signal to its closed position, a pull member for the said signal, a track-support, a guide thereon extending lengthwise 120 thereof, a pull member movable within the guide, an actuating means for releasing the detent for the spring-set signal, said actuating means including a flexible pull member, and a gravity-operated means normally supported by the track-support, connected with the pull member, and adapted when disabled 125 to effect a strain on the said member, for the purposes described.

CHARLES H. REMINGTON.
